Res. 133

James Wager, Troy, N.Y.

Letters Patent No. 233, dated September 25, 1849.

The schedule referred to in these Letters Patent and making part of the same.

To all to whom these presents shall come.

Be it known
that I, James Wager, of Troy, in the County of Rensselaer, and State of New York, have invented, or produced certain new designs for stove plates, and that the following is a full and clear description of them, reference being had to the accompanying drawings, making part of this Specification, in which figure 1 is a plan of a section of the top plate, and border, figure 2, a plan of a section of the side plate, figure 3, a plan of

507
a section of the front and back plates which are alike, and figure 5 a view of a section of one of the feet.

These designs are intended for the ordinary six plate stove, but are applicable to other kinds of stoves.

The top plate (a) (fig. 4) has a double moulding to all around, and a slightly waving border; the whole interior of the plate is plain. The bottom plate (c) (fig. 4) is ornamented with a border (d), formed of double leaves (e), which extends around the back and two sides of the stove. The front part of the base plate is ornamented with two heads (f) of birds, between which is represented a shell (f') containing flowers, and filled in with foliated tracery in the ogee form; the plate (g) which covers the ash pit is provided with a circular ornament (h), and the said plate is joined by the front plate of the stove, it is provided with an ornamental border.

The front or back plate (j) (see fig. 3) is panelled and decorated around the four edges and on the panel with foliated ornaments (k) in the ogee form.

The side plates (l) (fig. 2) are also panelled and provided with a rich border (m) of leaves; the panel contains in the centre an escutcheon (n) and is filled in with foliated tracery in the ogee style. A view of the feet is shown the lower half being formed of long leaves bound together about midway; the upper half is ornamented with leaves.

I claim as my invention or production the above described and illustrated designs for six plate stoves, and desire to secure the same Excl. by letters patent.
